UNITED STATES PATENT OFFICE.

SALOMON J. STAPPLER, OF NEW YORK, N. Y.

NAILING-MACHINE FOR SKINS AND THE LIKE.

1,315,645.

Specification of Letters Patent.

Patented Sept. 9, 1919.

Application filed May 8, 1918. Serial No. 233,368.

To all whom it may concern:

Be it known that I, SALOMON J. STAPPLER, a citizen of the United States of America, residing at New York city, Bronx county, State of New York, have invented certain new and useful Improvements in Nailing-Machines for Skins and the like, of which the following is a full, clear, and exact description.

10 This invention relates to improvements in nailing machines, and while my improved machine is arranged to automatically hammer nails, tacks or the like, it is especially intended for use in connection with other 15 coöperating elements to secure skins or the like to a suitable support, preferably a board carrier. In the manufacture of fur articles, the skins have to be prepared and cut to the desired shape. The preparing of the 20 skins consists in dampening and thereafter stretching same while damp to a suitable carrier and allowed to dry, after which the said skins are cut to the desired shape. My improved nailing device is arranged to 25 stretch the skins and to automatically fasten same to a board or the like. The above is an outline of my invention, further features of improvement appearing in the following description and drawings, showing 30 one embodiment of my invention, wherein:

Figure 1 is a side elevation of my improved machine;

Fig. 2 is a top plan view thereof showing chiefly the movable carrier and head;

Fig. 3 is an enlarged fragmentary detail view of the nail-feeding disk and chute;

Fig. 4 is an enlarged side view thereof;

Fig. 5 is an enlarged sectional view on line 5—5 in Fig. 3;

Fig. 6 is a similar view, the section being taken on a line 6—6 in Fig. 3;

Fig. 7 is an enlarged detail view of the type of tack or nail which I preferably 45 employ;

Fig. 8 is an enlarged sectional view of the nail-hopper, the section being taken on a line 8—8 in Fig. 1;

Fig. 9 is a fragmentary sectional plan 50 view thereof the section being taken on a line 9—9 in Fig. 8;

Fig. 10 is a similar view, the section being taken on a line 10—10 in Fig. 8;

Fig. 11 is a sectional side elevation of the 55 hopper, the section being taken on a line 11—11 in Fig. 8;

Fig. 12 is an enlarged detail side elevation of a stretching device associated with my improvements;

Fig. 13 is a plan view thereof; 60

Fig. 14 is a sectional view thereof, the section being taken on a line 14—14 in Fig. 13;

Fig. 15 is an enlarged detail end view of the hammer device and associated parts; 65

Fig. 16 is a sectional plan view of the hammer slide; the section being taken on a line 16—16 in Fig. 15;

Fig. 17 is an enlarged detail side view of the nail-extractor; 70

Fig. 18 is a detail perspective view of one of the extractor-jaws;

Fig. 19 is a similar view of one of the nail-clamps carried by the hammer;

Fig. 20 is an enlarged detail face view of 75 the kneading device;

Fig. 21 is a similar view, on a reduced scale, of the dampening device;

Fig. 22 is an enlarged fragmentary detail view of the head-end of the hammer; 80

Fig. 23 is an enlarged face view of a modified form of stretcher;

Fig. 24 is a plan view thereof;

Fig. 25 is a fragmentary perspective view of the twisted portion of said chute. 85

My improved machine is arranged to receive a skin, stretch the same, and finally nail the skin to a carrier, preferably a wood-board, to receive a nail or tack. To this end, I provide a suitable skeleton frame consisting of uprights 25 (Fig. 1) suitably secured to a floor or the like, at their lower ends, said uprights being connected by bracing-members 26, 26 and 27, 27 at the top thereof. Intermediate the ends of the uprights, I 90 provide connecting rails 28—28, to which are pivotally secured, intermediate their ends, carrier-supports 29, 29, said supports being pivotally or rotatably connected to said rails at 30. The supports 29 are arranged to removably retain a carrier 31, preferably a wood board to which skins, indicated by 32, may be attached. Before the skins are attached to the boards or carriers, they are dampened to render them stretchable. To dampen or apply water to the skins, I provide a dampening device consisting (in this instance) of a plurality of drums or rollers 33, 34 and 35, rotatably supported by a trough 36 containing water, indicated by 37. The lower portion of the rollers or drums 34 and 35 are immersed in 100

105

110

the water and the upper or pressure roller 33 rests upon the rollers 34 and 35. The roller or drum 33 is rotatably supported by an arm 39 pivoted to a bracket 40 carried by the trough 36 (Fig. 21). One of the rollers (in this instance, the roller 35) carries an operating handle 41. To dampen the skins, the upper roller will be lifted and the skin placed between roller 33 and rollers 34 and 35, after which the handle 41 will be operated to rotate the rollers, whereby the skin will be passed through the rollers, backward and forward, until the flesh side thereof is thoroughly damped or softened.

15 After the skins have been softened, they will be placed upon a board and secured thereto at the center thereof by a few nails, as indicated by 42 Fig. 2. After the skin has been thus fastened, the carrier or board 20 will be placed in the channeled supports 29 and secured by clamping screws 43. The supports are or may be provided with foldable braces 29^a to maintain them in a horizontal position. But other supporting 25 means for the carrier may be employed. The object of the rotatable supports for the carrier is to allow for two skins, for instance, to be secured to the carrier, one on each side. It would be quite possible to 30 secure a plurality of small skins to each side of the carrier, say for instance, two small skins on each side. After the carrier and its initially attached skin, or skins, has been placed in the carrier, the skins will 35 be secured to the carrier, after the skin has been stretched, by the application of nails which pass through the skin adjacent the edges thereof in order to avoid mutilating the skin any more than possible.

40 The nails or tacks which I employ, are preferably of special construction (see Fig. 7) but I do not limit myself to the use of any particular type of nail. The nails or tacks referred to are designed to withstand the impact of the hammer without 45 breaking, also to allow of ready extraction and to be used as often as desirable. To this end, I provide a tack or nail having a plurality of heads 43 and 44 connected by a 50 relatively thick shank 45, the lower head carrying a piercing point 46 long enough to pass through the skin and into the board or carrier 31. When the nail is driven home, the lower head 44 will be forced 55 against the skin, while the upper head will project above the skin. To force the piercing point through the skin into the board, I provide a special hammering device, which I will now proceed to describe.

60 *The hammering device.*

The hammering device includes a reciprocating hammer 47 carried by a slide 48 operating in a guide 49 secured to a motor 50.

The motor-shaft 51 (Fig. 1) carries a gear 65 52 meshing with a gear 53 carried by a shaft 54 mounted in a bearing 55 on the motor 50. The gear 53 is connected to the hammer-slide 48 by a link 56. The upper end of link 56 is pivotally connected to the 70 crank-pin 57 which carries an arm 58 directed toward the axial line of shaft 54. The arm 58 carries a supplemental stub-shaft 60, the axis of which is coincident with the axis of the shaft 54; hence said 75 stub-shaft will rotate concentrically with shaft 54. The stub-shaft 60 actuates a flexible shaft 61 which in turn actuates a nail or tack-feeder, indicated generally by 62. The hammer 47 consists of (in this instance) 80 two slidably connected parts, a body portion 63 connected with the slide 48 and a head 64 carrying a shank 65 slidably engaging a socket 66 in the body portion 63. The body portion 63 and head 64 are normally connected for mutual operation by means of a latch-pin 67 carried by the body portion which engages a notch 68 in the shank 65 (Fig. 23). The pin 67 and notch 68 are kept in engagement by a spring 69 85 located in a socketed extension or lug on the body member 63. The object of the above construction is to adapt the hammer-members to drive the nails or tacks, but to become disconnected one from the other 90 when the nail has been driven home, thereby preventing injury to the hammer parts. A spring 69^a acts to return the hammer-head to normal position after it has performed its function, as will hereinafter appear. 95

In combination with the hammer, I employ means to automatically feed nails or tacks thereto.

100 *The nail supply and feeding device.*

The nail or feed supply consists of a hopper 70 carried (in this instance) by the casing of the motor, a chute 71, and the before-mentioned feeding disk or device 62. The hopper is provided with a delivery pipe 72 through which the nails or tacks will pass into the hopper. Referring to Figs. 8 and 11, the hopper 70 consists of a fixed casing 73 which includes an annular flange 74 and a rotatable drum 75 within the casing. The drum is provided with a central chamber 76 to receive the nails or tacks. The remainder of the body 77 of the drum is provided with a series of channels 78 to conform to the shape of the nails or tacks illustrated in 110 Fig. 7, and hereinbefore described (see also Fig. 10). The drum carries a sprocket-wheel 79 connected by a chain 80 to a sprocket-wheel 81 on the motor-shaft 51 (see Fig. 1). During the operation of the device the drum 75 will be rotated. During the rotation of the drum the nails which have been poured into the chamber 76 will 115 120 125

be stirred up and threshed about therein. The nails which become positioned by the stirring and threshing to aline with the channels 78 will drop into said channels, 5 that is to say, when a nail becomes positioned to cause its larger head 43 to aline with the wider slot 82 of said channels, the nail will drop into said channel (see Fig. 10). The nails will not drop in until they 10 do aline. The chute 71, which conveys the nails away from the hopper, consists of the two channeled-members 83 and 84 (Figs. 5 and 6) having the channels presented toward each other, said members being spaced 15 apart to form a slot 85 to receive the piercing point of the nail or tack. The chute 71 will have its upper end located with respect to the channels in the hopper to cause the smaller head 44 of the nails to be received 20 within the channels of the chute-members, as shown, the larger head 43 being caused to ride upon the upper surface 86 of said chute-members. The entrance 87 to the chute 71 will be wide enough to insure the entrance 25 thereinto of the nails (see Figs. 10 and 11). The nail will be delivered to the chute in a horizontal position, but will be turned to a vertical position for delivery to the feeding disk 62 by the twisted portion 88 of the 30 chute 71. (See Fig. 25.) The feed device 62 consists of a disk 89 (Fig. 3) having peripheral recesses or pockets 90 to aline with the channels of the chute-members 83 and 84 (see Fig. 6). The disk 89 will be operated step by step, that is to say, advanced the 35 distance between two pockets each time the hammer is operated. During each operation of the hammer, which consists of a downward working stroke and a return idle 40 stroke, the disk 89 will be advanced one step by the Geneva-movement 91, the member 92 of which is connected to the stub-shaft 59 by the flexible shaft 61. The Geneva-movement will be set to rotate the disk while the hammer 45 is making a complete stroke. When the hammer comes to rest at the end of its idle stroke, a pocket 90, containing a nail, will have been positioned opposite to the nail clamp-members 93 and 94 carried by 50 the hammer (Figs. 1, 3 and 20), whereupon the nail in said pocket will fall between the said clamp-members. At such time, a pocket will have again alined with the nail chute and a nail will fall into said pocket; hence 55 at each operation of the feeding-disk, a nail will be delivered and one received. A guard 95 acts to prevent the nails in the pocket from falling out during their passage from the chute to the feeding disk. Each nail-clamp 93 and 94 carries a projection or step 60 96 (Fig. 20) to prevent the nails from passing through or between the clamps 93 and 94. The clamp-members 93 and 94 are yieldable or spring acting; hence after a nail has been driven in by the hammer, the 65 clamps 93 and 94 will spring over the head 43 of the nail during the return or idle stroke of the hammer.

In combination with the hammer, I provide a stretching device to place the skins 70 under tension while the nails are being applied, which I will now describe.

The stretching device.

The stretching device, in this instance, 75 consists of a pair of clamp-jaws 97 and 98 (Figs. 12 and 13) pivotally connected to each other and to a movable support 99 by a pin 99^a. The jaws will be kept normally separated by a spring 101. The clamp-member 80 98, which I will term the lower jaw-member, carries a plate 102 which rests upon the carrier and upon which the skin rests (see Fig. 12). The upper clamp-member also carries a plate 103 which engages the skin upon its 85 upper surface. The upper plate 103 is provided with a recess 104, for the passage of the hammer head, alining with a recess 105 in the lower plate 102 for the passage of the nail. The support for the clamp-members 90 consists (in this instance) of links 106, 107 pivotally connected at their upper end to a bracket 108 on the motor casing. (See Fig. 16.) A spring 109 which connects the extension 110 on the link 106 with the motor- 95 casing, serves to maintain the stretching device somewhat removed from a position under the hammer, when not in use, for reasons to be set forth.

To stretch a skin, the clamp-member will 100 be moved inwardly toward the skin, that is, for the initial engagement, causing the under plate 102, which is sharpened, to pass under the skin and the upper plate over the skin. The jaws will now be closed to cause 105 the plates 102, 103 to engage or grip the skin. After this operation the jaws will be pulled, as an entirety, in the direction of the arrow, Fig. 12, thereby stretching the skin, the central nails 42 (Fig. 2) acting as an 110 anchor. While the skin is under tension, or rather that portion gripped by the jaws, I apply a nail thereto, thus securing the skin to the carrier while under tension.

The engagement or gripping of the skin 115 by the relatively large plates 102 and 103 prevents tearing of the skin, the plates being recessed to allow the nail to be applied close to the edge of the skin (see Fig. 13).

To cause the hammer to operate while the 120 skin is under tension, I provide one of the clamp-members (in this instance 98) with a switch 111, said switch being included in the motor-circuit 112, such a switch being diagrammatically illustrated in Fig. 12. While 125 the skin is under tension, the operator will press the button of the switch to close the circuit for the motor, whereupon the ham-

mer will apply the nail. The clamp-jaws can now be released and the whole device moved to a new position for another stretching and nailing operation. When a nail is driven in, the lower head thereof will contact with the upper surface of the skin, but to prevent injury to the parts the connection between the hammer-head and body portion of the hammer will be released as soon as said lower head seats. In other words, should the lower head seat before the crank reaches its lower dead center, the connection between the hammer-head and body portion will release, and hence the remainder of the stroke of the body portion can continue without injury to the parts. Upon the return stroke, the spring 69 will restore the hammer-head to normal position.

Instead of manually stretching the skins, I may do so automatically by the device illustrated in Figs. 23 and 24. In this form the head 64 will be provided with a support 113 carrying a post-member 114 and a member 115 which also acts as an auxiliary post and carries a pressure spring 116. The post 114 has secured thereto at 117 a lower jaw 118 and an upper jaw 119. The jaws 118 and 119 are kept normally separated by a spring 120, the spring 116 being normally relaxed. When the hammer is lowered to apply a nail, the spring 116 will be compressed, thereby forcing the upper jaw down on the skin, the serrations thereon engaging the skin. A further downward movement of the hammer will cause the edge 121 of the slot 122, in which the post 114 is mounted, to contact with the inclined plate 123 on the post 114. A further downward action of the hammer will move the jaws as an entirety in the direction of the arrow, 124, thereby stretching the skin. The entire operation above described will take place before the nail reaches the skin. The plates 125 and 126 of the jaws 118 and 119 are recessed as at 127 and 128 for the passage of the nail and hammer-head.

As the contour of the skins to be treated will be irregular, the hammer device is mounted so that it can be caused to follow the said contour. For this purpose, I have provided a carriage 129 movable longitudinally of the frame of the device, said carriage supporting a head 130 movable longitudinally thereof and transversely of the frame. The motor 50 is pivotally secured to the head 130 by means of a bushing 131 and a therethrough passing trunnion-member 132 (Fig. 16). The carriage 129 consists of rails 133 secured at the ends to frames 134 carrying rollers 135 engaging the frame-members 27. The head 130 consists of a plate-member 136 carrying rollers 137 to engage the rails 133 of the carriage 129. It will be apparent that by means of

the movable carriage, movable head and rotatably supported hammering-device, the hammer can be caused to follow the irregular contour of a skin. But it is apparent that other means for supporting the hammer-device, motor and coöperating elements, may be employed without departing from the scope of my invention.

In combination with the nail applying devices, I provide an automatically operable nail extractor, which I will now describe.

The nail extractor.

The nail extractor, in this instance, comprises an endless chain 138 (Figs. 15 and 17) operated by a sprocket 139 on the shaft 54, said chain also passing around a second sprocket 140 adjacent the carrier 31. The lower sprocket is carried by a depending frame 141 pivotally supported by the shaft 54. The frame 141 carries an extension 142 having openings 143 and 144 to receive a pin 145 to hold the extractor in an operative position or in an idle position away from the skin. The chain 138 carries a plurality of jaws 146 (Fig. 18) to engage the nails between the heads thereof. During the operation of the chain, the jaws 146 will engage the driven in nails and pull them out, it being of course understood that the said jaws will be caused to aline with said nails by manipulating the carriage 129 and head 130. When the jaws are caused to aline with a nail, one at a time (the extractor being positioned as indicated in Fig. 1), the jaws will be moved to a position between the heads, straddling the shank during the movement of said jaws around the lower half of the sprocket 140; hence when the said jaws move upwardly, the nails will be pulled out. The dotted lines in Fig. 15 illustrate a nail engaged by a jaw.

To prevent the hammer from making more than a complete stroke each time the switch button is pressed, I provide a stop mechanism in the circuit arranged to prevent the crank from overrunning, consisting of pins 147 and 148 engaging openings 149, 150 in the gear 53, said pins being actuated by a magnet 151 operating on a bell-crank-lever 152. One pin at a time will engage the gear; for instance, should the pin 148 be in engagement when the switch is pressed, it would be pulled out, allowing the gear to rotate, the magnet 151 being in the motor-circuit. This action will force the pin 147 into contact with the gear in the path of movement of its opening 150. As soon as opening 150 alined with said pin, which would take place when the gear made a complete stroke, it would be forced thereinto by the magnetic pull, it being remembered that the current would be still on. The operator will release the button as soon

as the hammer comes to rest. The pins 147 and 148 will alternately act to prevent the gear from being overrun.

After the skins have been dried and cut 5 to the desired shape, they will be removed from the carrier and passed through a kneading or softening device to render same pliable. The kneading device consists of a plurality of drums or rollers 153 and 154 10 (Figs. 1 and 21), the roller 153 being provided with recesses 155 and the roller 154 with projections 156 alining with the same. During its passage between the rollers, portions of the skin will be pressed into the depressions or recesses by the projections. The action of pressing the skin into the depressions will act to bend or knead same, thereby rendering the skin soft. The upper 15 drum or roll is operated by a handle 157 affixed to its shaft 158. A frame 159 supports the shaft 158 and the shaft 160 for the under roller 154.

It will be understood that many of the details of construction hereinabove described 25 may be modified or changed in various particulars and equivalent mechanical expedients employed for accomplishing like results without departing from the general scope of my invention.

30 What I claim as my invention is:

1. In a skin stretching machine, a carrier adapted to receive the skins to be stretched, and means to automatically nail the skin to the carrier, said nailing means being arranged to be moved to follow the contour 35 of the skin.

2. In a skin stretching device, a reversible carrier adapted to receive the skins to be stretched on both sides thereof, means to 40 stretch said skins, and means to apply nails to the stretched portion of the skin while it is under tension.

3. In a skin stretching device, a carrier adapted to receive the skins to be stretched, 45 means to stretch the skins, an electrically operated nailing device, and means associated with the stretching device to control the operation of the nailing device.

4. In a skin stretching device, a carrier 50 adapted to receive the skins to be stretched, movably mounted jaws to engage the skins at the edge thereof, said jaws being arranged for movement to stretch said skins, an electrically operated hammer to apply nails to 55 the stretched portion of the skin, and a switch to control the operation of the hammer carried by said jaws.

5. In a skin stretching device, a frame, a carrier adapted to receive skins to be 60 stretched on both sides thereof, rotatably se-

cured thereto, means to stretch the skins, and means to apply nails to the stretched portions of the skins.

6. In a skin stretching and nailing machine, a carrier to receive the skins to be 65 stretched, a universally movable nail applying device adjacent thereto, links pivotally secured to the nail applying device, and a stretching device carried by the links.

7. In a skin stretching and nailing machine, a carrier to receive the skins to be stretched, a universally movable nail applying device adjacent thereto, links pivotally secured to the nail applying device, and a stretching device carried by the links, 70 consisting of a plurality of coating clamping jaws to receive therebetween the edge of the skin.

8. In a skin nailing device, a reversible carrier to receive skins on both sides thereof, 80 and a universally movable nail applying device adjacent said carrier.

9. In a skin nailing device, a reversible carrier to receive skins on both sides thereof, a movable head adjacent the carrier, and a 85 nail applying device pivotally secured to said head.

10. In a skin stretching and nailing device, a substantially flat carrier adapted to receive skins to be stretched, a nailing device 90 arranged to follow the contour of the skins, and means associated with the nailing device arranged for movement to stretch the skins horizontally without moving the nailing device.

11. In a skin stretching and nailing device, a carrier adapted to receive skins to be stretched, a nailing device arranged for universal movement in a horizontal plane only, and means adjacent thereto, arranged for 100 movement to stretch the skins without moving the nailing device.

12. The combination of a nailing device arranged for universal movement in a horizontal plane, and a stretching device associated therewith arranged for movement independently of the nailing device.

13. The combination of a nailing device arranged for universal movement in a horizontal plane, a stretching device attached 110 thereto and movable therewith arranged to be moved toward or away from the nailing device without moving said nailing device.

Signed at New York city, N. Y., this 6 day of May, 1918.

SALOMON J. STAPPLER.
